CANDLE DISPLAY BOX

Christopher Carruthers Sandidge, Los Angeles, Calif.,
assignor to Sue Sherwood, Simi, Calif.

Filed July 17, 1972, Ser. No. 272,490

Term of patent 14 years

Int. Cl. D20—02

U.S. Cl. D6—189

Fig. 1

Fig. 2

FIG. 1 is a front upper perspective view of a candle display box embodying my new design; and

FIG. 2 is a front upper perspective view of another form of candle display box embodying the subject design.

The top and back panels of both forms are plain, while the undisclosed sides are mirror images of the sides shown.

I claim:

The ornamental design for candle display box, substantially as shown and described.
